Dec. 1293

Benjamin S. Pardee, of Mount Carmel, Conn.
Letters Patent, No. 1293, dated July 1, 1860.

The schedule referred to in these Letters Patent and making part of the same.

To all whom it may concern:

Be it known that I, Benjamin S. Pardee, of Mount Carmel, in the County of New Haven, and State of Connecticut, have invented or provided a new and original design for Hub Bands, and I do hereby declare that the following is a full, clear and exact description of the same, reference being had to the annexed drawings, making a part of this Specification, in which -

Figure 1. is a face view of a hub band showing my design.
Figure 2. a side view of ditto, partially bisected.

Similar letters of reference indicate corresponding parts in the two figures. This invention relates to a new and original design for the metal bands which are placed on the outer ends of wheel-hubs, and has for its object the giving of the bands an ornamental taper form from their inner to their outer ends.

In the drawings A. is the band which may be of cast iron, brass, white metal, or other metal or composition, which may be used for such purpose.

The hub-band A. is made of taper form by having two step-like declivities a. b. the outer one b. being smaller in diameter than a. and the latter smaller in diameter than the inner part c. of the band as shown clearly in figure 2.

This manner of tapering the hub-band gives it a very chaste and neat appearance, and destroys the monotonous effect attending a smooth taper form.

Having thus described my invention, what I claim as new & desire to secure by Letters Patent, is -

A hub-band made of taper form from its inner to its outer end, by means of the step-like declivities a. b. the same forming a new and original design for the article specified.
